CLAIM

The ornamental design for an analyte sensor device, as shown and described.

DESCRIPTION

(63) Continuation of application No. 15/908,616, filed on Feb. 28, 2018, which is a continuation of application No. 15/610,334, filed on May 31, 2017, now Pat. No. 9,931,066, which is a continuation of application No. 15/193,499, filed on Jun. 27, 2016, now Pat. No. 9,693,713, which is a continuation of application No. 13/710,460, filed on Dec. 11, 2012, now Pat. No. 9,402,570.

FIG. 1 is a front perspective view of an analyte sensor device with an applicator shown in broken lines to illustrate environment;

FIG. 2 is a right perspective view thereof;

FIG. 3 is an enlarged view of area 3 of FIG. 2;

FIG. 4 is a top plan view thereof;

FIG. 5 is a bottom plan view thereof;

FIG. 6 is a front side view thereof;

FIG. 7 is a left side view thereof;

FIG. 8 is a right side view thereof; and,

FIG. 9 is a rear side view thereof.

The dashed broken lines showing an applicator in FIG. 1 illustrate environment and form no part of the claimed design. The dot-dash broken lines in the drawings encircling portions of the claimed design that are illustrated in enlargements form no part of the claimed design. The remaining broken lines in the drawings illustrate portions of the analyte sensor device that form no part of the claimed design; the broken lines and the unshaded surfaces immediately adjacent the broken lines form no part of the claimed design.
